[57] CLAIM

The ornamental design for a deer scent dispenser, substantially as shown and described.

DESCRIPTION

FIG. 1 is a perspective view of a deer scent dispenser; FIG. 2 is a front elevation view thereof;

FIG. 3 is a side elevation view thereof;

FIG. 4 is a rear elevation view thereof; and

FIG. 5 is a bottom view thereof.

The dotted lines in FIG. 1 are shown for illustrative purposes only and form no part of the claimed design.
